EARRING

Maurice Joseph Dweck, 11 W. 30th St.,
New York, N.Y. 10001

Filed May 15, 1967, Ser. No. 7,126

Term of patent 3½ years

(Cl. D45—9)

FIG. 1 is a side elevational view of an earring showing my new design;

FIG. 2 is an end elevational view thereof, as seen from the left hand portion of FIG. 1;

FIG. 3 is a side elevational view thereof, showing the side opposite that seen in FIG. 1;

FIG. 4 is an end elevational view thereof showing the end opposite that seen in FIG. 2;

FIG. 5 is a top plan view thereof; and

FIG. 6 is a bottom plan view thereof.

The dominant feature of my new design lies in the provision of a flat centrally disposed geometric design set within a flat curve member which encompasses the center element of an earring all as shown.

I claim:

The ornamental design for an earring substantially as shown and described.
